5 Claims

ABSTRACT OF THE DISCLOSURE

The disclosure hereof relates to trip lever bath drains and particularly to a way of initially adjusting the plunger or seating member thereof to establish shut-off of water flow to the waste arm of a trip lever without having a trial and error manipulation, the initial establishment of the shut-off position being effected after the installation and not requiring any disassembly or subsequent manipulation of the parts, once the seating position is established it being maintained thereafter without further adjustment required. The concept further involves the provision of means to permit a relative one-way movement so to speak of the interconnection between the operating parts of the trip lever and the plunger so that the one-way movement can be effected and yet subsequent manipulation will permit regulation of the waste flow through the drain.

This invention relates to bath drains and more particularly to a bath drain in which the shut-off means provided therein is automatically adjustable in accordance with the adjusted height of the bath drain which is determined by the height of the bath tub and the overflow opening therein.

In bath drains of the usual construction, which involve the use of a trip-lever arrangement, the bath drain requires a substantial amount of manipulation in its original installation in order to assure the proper seating of the plunger therewithin, and in most cases requires the installation to be made by two persons so that proper shut-off control of the flow of waste water from the tub is provided.

Further than the foregoing, when the bath drain is ultimately installed, and it is desired to position the shut-off means therewithin, a great deal of trial and error is involved since there are adjustable portions of the connections of the shut-off member with the control lever and predetermining the exact location of one with respect to the other is not always feasible and if it is accomplished, usually accidentally.

In view of the foregoing, the contemplation of the instant invention is to provide a bath drain which may be simply installed and when installed the control means for waste flow therefrom may be readily positioned, instantly adjusted in position so that it shuts off accurately time after time without any trial and error such as required in prior art devices.

A further object of the invention is to provide a simple construction which is positive in its action and which may be useful over a wide range of bath tubs as to the relative distances between the overflow opening therein and the T which is part of the bath drain and through which the waste water flows when in use.

A further object of the invention is to provide a simple lift rod structure and engagement with the plug or plunger in the trip lever, so as to effect instantaneous adjustment of one with relation to the other upon installation.

An even more particular object of this invention is to provide a bath drain in which the control means includes the usual control lever, in this instance pivotally arranged,

2

to raise and lower a lift rod, which lift rod includes a resilient section therein, and the end of the lift rod is provided with a gripping member adapted to co-act with the plug or plunger frictionally engaged with the lift rod so as to be adjustable relative thereto during initial installation of the control means to thereafter provide accurate opening and closing movement of the plug or plunger to open and shut the waste arm to provide drainage from the tub or similar instrumentality.

Other and further objects of the invention will be understood from a consideration of the specification and disclosed in the drawing wherein:

FIGURE 1 is a vertical section view through a bath drain showing the relationship of the parts thereof and the instrumentalities provided for the self-adjusting action.

FIGURE 2 is an enlarged fragmentary vertical sectional view showing more particularly the engagement of the lift rod and plug or plunger together with the gripping member provided therefor.

FIGURE 3 is an enlarged view in elevation showing the gripping member.

FIGURES 4, 5 and 6 are fragmentary views partly in section showing various means for retaining the connection of the plug or plunger and lift rod.

Referring to FIGURE 1, the trip lever disclosed therein, is shown as being mounted on a bath tub generally designated 1 and having particular spacing of the overflow opening 2 therein with respect to the bottom 3 of the tub, which may advantageously avail of the adjustable nature of the trip lever itself, which trip lever is designated 4 and includes a waste T 5, having a shut-off seat 6 therein, which is adapted to cooperate with a plunger 7 to maintain the water in the tub when the plunger or plug 7 is seated on the seat 6, by shutting off the waste arm generally designated 8 comprising a waste shoe 9, adjustably connected with the arm 8 by means of a suitable slip nut 10. The waste shoe is connected to an outlet opening 11 in the tub in the usual manner by a suitable waste plug generally denoted 12.

The waste T 5 is provided with an outlet 13, connected to any suitable drain in the usual manner, the waste T in turn being provided at its upper end with an overflow arm designated 14 generally and comprising a lower member 15 having a suitable slip nut 16 with the packing 17 therein for engagement with the upper member 18, at the upper end of the latter there being provided the usual overflow head 19 connected to the overflow opening 2 previously mentioned, in any conventional manner.

The overflow head 19, is intended to provide for the overflow of water in the bath tub if it reaches the overflow opening, and likewise provides a location for the control means generally designated 20 which includes a control lever 21 pivotally mounted in the face plate 20a which latter is connected to the overflow head 19 in any conventional manner not here further described.

The lever 21, is arranged to raise and lower a lift rod 22, which rod 22 is pivotally connected at its upper end to the lever 21 by a unique connection 23 and at its lower end provided with the connection to the plug or plunger 7 which involves the self-adjusting feature hereinbefore generally described.

The connection 23 is effected by a double loop including the members 23a and 23b which in conjunction with the end portion 23c of the lever 21 eliminate the necessity for a cotter pin connection, and yet make possible rapid assembly. The double loop arrangement prevents disconnection of the two parts and also makes available sufficient pressure to close the plug or plunger 7.

In connection with self-adjusting arrangement, FIGURE 2 is referred to, and discloses that the plug or plunger 7 includes in this particular instance a wrought member or body having a portion 25 at the lower end thereof

adapted to co-act with the seat 6 to shut-off water flow, and at its upper portion being cylindrical and hollow, formed with a transversely extending bail member 26 which may be formed up out of the material from which the plug or plunger 7 is itself formed, and provided with an opening 27 therein through which the lift rod 22 is entered.

The lower end of the lift rod 22 in this instance is deformed in a manner such as is suggested at 28 to provide a gripping action with the gripping member generally designated 29 and more particularly itself shown in FIGURE 3.

The gripping member 29 is a wire form member including a series of coils indicated at 30, these coils comprising a gripping section, which closely engage the lift rod 22 and is connected to a second like gripping section 31 spaced therefrom by means of a connecting portion 32.

It is understood that these coiled sections 30 and 31 are arranged so that the axes 30a and 31a thereof intersect at an angle with respect to one another and when positioned on the lift rod 22 thus actually closely frictionally grip the said rod in this instance above and below the bail 26.

It will thus be understood that the plug or plunger 7 may be raised and lowered by the lift rod 22 in conjunction with the gripping member 29 during operation of the member 7 for drain or water retention purposes.

The lift rod 22 is formed intermediate its ends with a resilient section 30 which will compensate for some slight variations or for an obstruction which might become lodged on the seat 6 and otherwise prevent the closing action of the plunger 7, in effect thus providing for slight variations which occur from time to time in the seating of the said plunger such as by soap or other matter which would not actually interfere with the closing but which would vary the operating distance thereof.

With the foregoing various elements having been described, the actual advantages of the invention will be understood when it is explained that after the trip lever including the T, waste arm, overflow arm, overflow head and other parts are assembled on the tub, it is necessary to subsequently insert the means to shut off the water, involving the lift rod 22, the lever 21 and plunger 7.

In order to facilitate this action and to illustrate the advantages of the arrangement described, it will be explained that the plunger or plug is positioned at the lower extremity of the rod 22 with gripping member 29 in position about as shown in FIGURE 2, and thereafter the plug or plunger 7, lift rod 22 and control lever 21 assembled with the face plate, are inserted through the opening 2, and downwardly in the overflow arm 14, with the lever pivoted into its position opposite that disclosed in the FIGURE 1. The plunger is thus positioned on the seat 6, and by manipulation of the control lever 21 into the position shown in FIGURE 1, the lift rod 22 is caused to move downwardly with respect to the bail 26 so that the gripping member 29 and the coils of wire which surround the lift rod 22 slide frictionally with respect to one another to the extent necessary to bring the unit into the position of FIGURE 1. This is the closed position of the unit and it will be observed that no trial and error was involved since the lift rod 22 moves initially in its positioning in respect to the plunger 7 but thereafter the gripping action of the gripping member 29 upon manipu-

lation of the control lever 21 will raise and lower the plug or plunger 7 and thus control the flow of water through the waste arm. It is clear that there was no other manipulation than the mere forcing of the rod 22 downwardly with respect to the gripping member 29 which is in co-action with the bail 26 of the plug or plunger 7 thus enable the establishing of the relationship ultimately desired to be maintained by the said gripping member.

The lift rod 22 may desirably be provided with any preferred means of preventing the plug or plunger 7 from being disconnected therefrom while it is used as an operating member, and to this end FIGURE 4 shows the end of the rod 22 being upset at 35, in FIGURE 5 the end of the rod is bent at an angle as indicated at 36 and in FIGURE 6 the end of the rod may be threaded and provided with a nut as indicated at 37.

I claim:

1. In bath drain construction of the class described, in combination, a waste T, a shut-off seat in said T, a shut-off plunger operable toward and from said seat to control flow of liquid through said T, a waste arm connected to said T to direct liquid thereto, an overflow arm extending from said T, an overflow head at the end of said arm, and control means extending from said head to the plunger, aforesaid, said control means comprising a control lever mounted in the head, a lift rod extending from the lever and connected to the said plunger, the connection consisting of a gripping member frictionally engaging the lift rod and connecting the plunger thereto, said connection providing for initial relative movement of the rod and plunger in one direction to facilitate initial seating of the plunger on the seat in the T, and opening and closing operation of the plunger thereafter by said lever.

2. The combination as claimed in claim 1, wherein the control lever is pivotally mounted in the head and arranged to raise and lower the lift rod in the overflow arm, the plunger includes a bail for connection of the rod and plunger, and the gripping member comprises a spring clip having a pair of gripping sections, one each at opposite sides of the bail, and a portion connecting said sections to maintain the spacing therebetween.

3. The combination as claimed in claim 2, wherein the gripping member is formed of wire, the gripping sections consist of series of coiled loops closely engaging the lift rod above and below the bail, and the connection portions extend between said sections.

4. The combination as claimed in claim 2, wherein the lift rod includes means at the end thereof to increase the frictional engagement of the gripping member therewith.

5. The combination as claimed in claim 2, wherein the lift rod includes means at the end thereof to prevent disengagement of the plunger and rod.
